US00D490677S

(12) **United States Design Patent** (10) Patent No.: **US D490,677 S**
Chung et al. (45) Date of Patent: **** Jun. 1, 2004**

(54) **ELECTRIC DRILL**

(75) Inventors: **Godfrey Ka Wai Chung, Tuen Mun (HK); Taku Ohi, Greer, SC (US); Kenneth M. Brazell, Piedmont, SC (US)**

(73) Assignee: **One World Technologies, Limited, Hamilton (BM)**

(**) Term: **14 Years**

(21) Appl. No.: **29/188,022**

(22) Filed: **Aug. 12, 2003**

(51) LOC (7) Cl. **08-01**

(52) U.S. Cl. **D8/68**

(58) Field of Search .... **D8/14.1, 61, 62, D8/63, 64, 65, 66, 67, 68, 69, 70; 81/57.11, 429, 464, 465, 466, 469, 489; 173/13, 169, 178, 213, 217; 227/8, 114, 120, 130, 136, 142; 310/50; 408/20, 124, 125, 234, 241 R; 451/358**

(57) **CLAIM**

The ornamental design for an electric drill, as shown and described.

DESCRIPTION

FIG. 1 is a left side perspective view of the electric drill of the present invention;

FIG. 2 is a right side elevational view thereof;

FIG. 3 is a left side elevational view thereof;

FIG. 4 is a front end view thereof;

FIG. 5 is a rear end view thereof;

FIG. 6 is a bottom view thereof; and,

FIG. 7 is a top view thereof.
